IDENTIFICATION MEANS FOR RIBBONS AND THE LIKE

Application filed October 3, 1929. Serial No. 397,139.

This invention relates to identification means for ribbons and the like.

The object of the invention is to provide a simple and efficient means whereby the quality or source of manufacture of a ribbon, band, or similar sheet material may be identified readily while at the same time not being normally perceivable when the article is in use.

10 In the ribbon industry and particularly in that portion of it having to do with hat bands, there are thousands of shops using thousands of ribbons yearly as replacements in the renovating of old hats of high grade. It is 15 also a fact that many of these shops use inferior bands either knowingly or unknowingly, and this is highly objectionable because such a band impairs the appearance of the renovated job and because the band will wear 20 out and unravel rapidly and make the hat look very shabby.

It is highly desirable therefore there be provided a very simple way in which the shop keeper and the people who want to buy new 25 bands for their hats may be able to ask for and obtain bands of known high quality and to be able easily to ascertain that a given band is of the right make as demanded.

To this end the invention provides an 30 identification element disposed within the ribbon, band, and the like, normally hidden from view, which by slightly unravelling the end filler threads, will become clearly perceivable so that the user will instantly know 35 that the band has been made by a manufacturer recognized for the high quality of his goods and will therefore know that they have high quality goods on their hats either new or renovated. This same line of reasoning 40 also applies to other and similar material besides hat bands as may well be understood.

45 Preferably the identification element comprises a thread unit preferably woven within the ribbon or band, preferably along the selvage edge thereof, and so disposed there- 50 within that it is normally hidden from view except when the filler threads on the end of the ribbon are unravelled slightly.

55 Further and more specific objects, features, and advantages will more clearly ap-

pear from the detailed description given below when taken in connection with the accompanying drawings which form part of the specification and which illustrate one present preferred form of the invention.

55

In the drawings,

Fig. 1 is a partial elevation of a ribbon with the ends slightly unravelled to show the invention; and,

Fig. 2 is an enlarged separate view of the 60 identification unit by itself.

As shown in the drawings, the invention is applied in a preferred form thereof, to a ribbon having warp threads 10 and filler threads 11 which are woven in the usual 65 manner to provide a ribbon having the selvage edge 12.

Along and within the selvage edge of the ribbon or band is disposed an identification element A which is preferably of any desired 70 and distinctive color to distinguish it from the color of the ribbon threads. This thread unit only is perceivable when the end filler threads are slightly unravelled and yet it is 75 very easy to so identify the goods when desired.

As shown in Fig. 2 the identification 80 thread unit is preferably composed of a central core thread 13 around which is wrapped or spun, rather closely, a second thread 14. Either or both of these threads is of a distinctive color and because of the manner in which they are related they will readily pull out when it is desired to identify the goods 85 as above described.

It is obvious from the above description 90 that there has been provided a simple and yet absolutely certain means for telling the quality and origin or manufacture of the goods without impairing in any way the use or appearance in use of the goods. This is achieved by hiding in the ribbon an element of distinctive appearance such as color which can be examined by slightly unravelling the ribbon at its ends when desired.

95 While the invention has been described in detail and with respect to a preferred present form thereof, it is to be understood that it is not intended to be limited to such details and forms since many changes and 100

modifications may be made and the invention embodied in other forms without departing from the spirit and scope of the invention in its broadest aspects. Hence it is desired to cover any and all forms and modifications coming within the language or scope of any one or more of the appended claims.

What is claimed, is,

- 10 1. Identification means for ribbons and the like which comprises a thread woven within the selvage edge of the ribbon and normally hidden from view and having a distinctive color, the thread being visible only when the ribbon is slightly unravelled.
- 15 2. Identification means for ribbons and the like which comprises a thread unit woven within the ribbon along the selvage edge thereof and normally hidden from view and having a distinctive color, said unit comprising a central core thread and a second thread wrapped therearound throughout its length.

Signed at New York City, borough of Manhattan in the county of New York and State of New York this 2nd day of October, A. D. 1929.
